UNITED STATES PATENT OFFICE.

FREDERICK KNAPP SMITH, OF NEW YORK, N. Y.

TOILET-BOX.

1,095,744.

Specification of Letters Patent.

Patented May 5, 1914.

Application filed September 5, 1913. Serial No. 788,254.

To all whom it may concern:

Be it known that I, FREDERICK K. SMITH, of New York city, in the county of New York, in the State of New York, have invented new and useful Improvements in Toilet-Boxes, of which the following, taken in connection with the accompanying drawings, is a full, clear, and exact description.

This invention relates to certain improvements in toilet boxes and pertains more particularly to a toilet box adapted to be carried in an ordinary hand bag, for ladies' use when separated from the usual source of toilet article supply.

The primary object of the invention is to produce a box of compact construction and neat appearance formed with a plurality of compartments adapted to receive and separately confine toilet articles as powder, powder puffs, comb, mirror, etc.

A further object is to provide covers independent of the box cover, for those compartments adapted to contain readily dispersible material and preferably to mount these covers upon a single axis so as to consume a minimum space.

Another object is to provide a removable support for the covers which shall be readily positioned in operative relation in the initial assembling of the device and equally readily removable from the box if desired.

In the drawings Figure 1 is a perspective view of the box. Fig. 2 is a similar view with the cover in open position. Fig. 3 is a view similar to Fig. 2 showing the compartment covers raised. Fig. 4 is a view similar to Fig. 3 with the front of the box and the longitudinal partition, each partly broken away to disclose the support for the compartment covers and the separate compartment receptacles.

The device comprises a box-like casing —1—, preferably rectangular in form as shown, and a bottom —2— formed therewith or connected thereto in any suitable manner. A cover —3— formed with an edge flange —4— is hinged to the casing —1— in any suitable manner as by a hinge —5— and is adapted to swing or turn upon the hinge so that the flange —4— rests upon the casing —1— and forms substantially a continuation thereof.

The casing —1— is provided with a projecting knob —6— formed therewith or connected thereto in any suitable manner, as by soldering, and the cover —3— is provided

with a catch-plate —7— connected thereto in any suitable manner and provided with an opening —8— within which the knob —6— is adapted to seat itself when the box is closed and thereby lock the same. The inside of the cover —3— is provided with a mirror —9— which may be of any desired size except as limited by the size of the cover and the mirror may be attached to the cover in any suitable manner as by cement, glue, etc.

The interior of the casing —1— is divided into two longitudinal compartments —10— and —11— respectively by means of an upright wall or partition —12— having portions cut away to form notches or concavities —13— and —14— respectively for a purpose hereinafter specified. The compartment —11— is divided into two separate chambers or compartments —15— and —16— by means of a partition —17—, preferably as shown, having two upright diverging legs formed of plates —18— and —19—, each extending the width of the compartment —11— and having journals —20— and —21— respectively formed upon their upper edges and preferably integral with both plates —18— and —19— as shown, for the reception of a rod —22— adapted to form an axis and support for the covers —23— and —24— for the compartments —15— and —16— respectively.

The cover —23— is provided with a single journal —25— preferably formed integral therewith and positioned centrally on the rod —22—, while the cover —24— is provided with two spaced journals —26— and —27— and positioned on the rod —22— on either side of the journal —25— so that each cover has a hinged relation with respect to the partition —17— and is of sufficient size to substantially close its respective compartment.

The chambers —15— and —16— are provided with separate receptacles —28— and —29— respectively, readily insertable therein and removable therefrom and tightly confined by the wedging action of the partition —17— and adapted to receive the powder and powder puff respectively, and the covers —23— and —24— close these chambers independently of the cover for the box as a whole and prevent contact of the materials confined therein with the mirror —9—. The notches —13— and —14— permit the receptacles to be readily grasped for removal.

The longitudinal partition —12— is preferably provided with a projection —30— having an opening therethrough adapted to receive one end of the rod —22— and form a bearing therefor and to more firmly support the rod, the partition —17— and the covers —23— and —24— respectively and to properly space the chambers or compartments —15— and —16— and hold the covers in proper relation to close these chambers.

The compartment —10— may be used for holding a comb or other desired article.

It is apparent that the box may be made 15 of any suitable or desirable material but preferably of some more or less precious metal as gold, silver, nickel, etc., dependent upon the particular desire of the purchaser and the price for which these articles are to 20 be sold.

The partitions, the receptacles and the covers may likewise be formed of any suitable or desirable material, either wood or metal, and may or may not be of the same 25 material as the casing, in some cases glass being preferable for the receptacles, and that the size of the box and the arrangement of the compartments may be varied without departing from the spirit of this invention 30 as set forth in the appended claims.

What I claim is:

1. A toilet-box having an upright partition dividing the box into compartments, compartment covers, said partition formed 35 of diverging plates having bearings formed upon their top edges and common to both plates and means in said bearings hingedly connecting the covers thereto.

2. A toilet-box having a partition formed of diverging members dividing the box into 40 separate compartments gradually decreasing in width toward their bottoms, separate receptacles fitted into said compartments and held by the wedging action of the partition, bearings common to both members of said 45 partition, compartment covers and means in said bearings hingedly connecting the compartment covers thereto.

3. A toilet box having a longitudinal partition dividing the box into two compartments, a transverse partition dividing one of said compartments into two chambers, spaced bearings formed upon the transverse partition, a bearing formed upon the longitudinal partition and alined with the bearings upon the transverse partition, a rod seated in said bearings and covers for said chambers hinged upon said rod.

4. A toilet-box having a longitudinal partition dividing the box into two compartments, a transverse partition formed of spaced members and dividing one of said compartments into two chambers, bearings formed upon the transverse partition and common to both members thereof, a bearing 65 formed upon the longitudinal partition and alined with the bearings upon the transverse partition, covers for said chambers and means in said bearings hingedly connecting the covers thereto.

In witness whereof I have hereunto set my hand this 21st day of August, 1913.

FREDERICK KNAPP SMITH.
